Specification of Letters Patent.

Patented May 9, 1916.

Application filed March 13, 1912. Serial No. 683,616.

To all whom it may concern:

Be it known that I, WILLIAM C. STEWART, a subject of the King of Great Britain, residing at Lynn, in the county of Essex and State of Massachusetts, have invented certain new and useful Improvements in Stop Mechanism; and I do hereby declare the following to be a full, clear, and exact description of the invention, such as will enable others skilled in the art to which it appertains to make and use the same.

This invention relates to improvements in stop mechanisms and more particularly to reversing stop mechanisms by which the forward motion of the shaft is arrested, and the shaft is then given a reverse movement to bring the parts of the machine to stopping positions.

In many machines, particularly in sewing and other machines employed in boot and shoe work, it is desirable upon the completion of the work to stop the machine always at a certain and definite point in a cycle of operations. In certain machines it is desirable after the forward movement of the machine is arrested to impart to the driving shaft and thereby to the mechanism of the machine a reverse or return movement. In chain stitch sewing machines this return movement is particularly desirable since by this movement the needle is caused to cast off the last loop thereon to permit the work to be withdrawn. Certain mechanisms have been devised for obtaining these desired results which act to yieldingly arrest the forward rotation of the shaft and then rebound to impart a return or reverse movement to the shaft. Such mechanisms are usually controlled by a spring or an air cushion and operate yieldingly to arrest the forward rotation of the shaft through the yielding resistance of the spring or the air. After the forward rotation of the shaft is arrested, the reaction or rebound of the spring or air cushion acts to impart a reverse movement to the shaft. Since in machines provided with mechanisms of this type the speed of rotation of the shaft may vary between wide limits at the various times at which the stop mechanism is thrown into operation, the speed of the return movement of the shaft imparted by the rebound of the spring or the air cushion varies also between wide limits. It has therefore been difficult to arrest the return movement of

the shaft at a definite point in the rotation thereof without undue shock or vibration.

The primary object of the present invention is to produce a stop mechanism by which the forward rotation of a shaft may be arrested, a return movement imparted thereto, and the shaft brought to rest at a predetermined constant position in a rapid, certain and reliable manner without undue shock or vibration.

With the above object in view, one feature of the invention contemplates the provision in a stop mechanism of a rebound mechanism acting to yieldingly arrest the forward rotation of the shaft to impart thereafter a return movement to the shaft and a brake device acting in timed relation to the rebound mechanism to slow the shaft down to a predetermined speed before the arresting mechanism is brought into action. This provision insures that the shaft will always rotate at a constant speed during its return movement. Means is provided to cause the arresting mechanism to be brought into position at least a predetermined interval after the brake is applied so that a material braking interval is secured. In the preferred form of the invention the rebound mechanism comprises a cylinder and a piston arranged to operate in the cylinder and is constructed and arranged so that upon further forward rotation of the shaft after the parts of said mechanism are placed in relative operating positions the piston is operated in the cylinder to compress the air therein, the air forming a yielding cushion acting to yieldingly arrest the forward rotation of the shaft. When the forward rotation of the shaft has been arrested the reaction or rebound of the air which has been placed under compression in the cylinder acts to force the piston outwardly, thereby imparting a return movement to the shaft.

Certain other features of the invention relate to improvements in the mechanism for arresting the forward rotation of the shaft and for imparting a return movement thereto whereby the forward rotation of the shaft is quickly arrested without undue shock or strain on the mechanism.

Further features of the invention consist of certain constructions, arrangements and combinations of parts, the advantages of which will be obvious to one skilled in the art from the following description.

In the drawings illustrating the preferred form of the invention, Figure 1 is a view in side elevation of the stop mechanism applied to the main shaft of a welt and turn 5 sewing machine of a type well known in the art; Figs. 2^a and 2^b together constitute a view in side elevation of a portion of the stop mechanism, certain parts thereof being shown in section; Fig. 3 is a plan of the 10 stop mechanism; Fig. 4 is a sectional view of the stop mechanism taken on the line 4—4 of Fig. 1, looking in the direction of the arrows; Fig. 5 is a section taken on the line 5—5 of Fig. 2^a; Fig. 6 is a plan of a portion of 15 the frame upon which certain parts of the stopping mechanism are mounted; Fig. 7 is a sectional elevation of the cylinder and piston forming a part of the stop mechanism; and Fig. 8 is a view in side elevation of the 20 lower portion of the machine, illustrating particularly the main driving mechanism in the base of the machine and the connections between the treadle and the stop mechanism.

In the drawings the stop mechanism has 25 been illustrated as applied to the main shaft 1 of a welt and turn shoe sewing machine. Inasmuch as the construction, arrangement and mode of operation of parts of the sewing machine of the type illustrated in the 30 drawing are well known to those skilled in the art, no detailed description of the same is made herein.

In the drawings the various parts of the stop mechanism have been illustrated in the 35 positions which they assume when the shaft has been brought to rest. The mechanism for arresting the forward rotation of the main shaft 1 and for imparting a return movement thereto comprises a lever 2 pivotally 40 mounted on a shaft 3 and also arranged to slide longitudinally of said shaft. The forward end 4 of this lever overhangs the main shaft 1 of the machine and is formed with a cam surface 5, the forward portion of which 45 is nearly concentric with the shaft 1 and the rearward portion of which curves inwardly toward said shaft. When the lever 2 is in the position illustrated in Fig. 4 and in full lines in Fig. 3, the forward portion of the 50 lever lies in the path of a cam roll 6 mounted on the hand wheel 7, said hand wheel being secured to the shaft 1 so as to rotate therewith. When, therefore, the shaft 1 is rotated in the direction of the arrow (Figs. 2^a and 2^b) and the lever 2 is in stopping position, cam roll 6 will engage the cam surface 5 of said lever and by the movement of the cam roll along this cam surface the lever 2 will be rotated to the left (Figs. 2^a and 2^b) 55 about the shaft 3. On account of the construction of the cam surface 5, as above described, the angular movement of the lever 2 for the same angular movement of the shaft 1 increases rapidly as the cam roll 6 approaches the rearward portion of said sur-

face. The rear extremity 8 of the lever 2 is connected by means of a ball ended link 9 with a piston 10 which is arranged to operate in a cylinder 11. The said cylinder is provided with an inlet port 12 controlled by 70 a valve 13 which is constructed to permit the free entrance of air into the cylinder but to prevent the exhaust of air therefrom through the said port. When the lever 2 is rotated in a left-hand direction (Figs. 2^a and 2^b) by 75 the engagement of the cam roll 6 with the cam surface 5, the piston 10 is moved inwardly in the cylinder 11 compressing the air within the cylinder which forms a yielding and progressively increasing resistance 80 to the movement of the lever 2 and to the forward rotation of the shaft 1. When this resistance becomes sufficient to overcome the momentum of the machine the forward rotation of the shaft 1 is arrested. Immediately thereafter the reaction or rebound of the air within the cylinder 11 imparts an outward movement to the piston 10 and through the connection of the piston with the lever 2 and the engagement of cam surface 5 on the lever with the cam roll 6 imparts a reverse or a return movement to the shaft 1. 85

When the lever 2 is in the position indicated in dotted lines in Fig. 3, the forward 90 extremity of said lever is out of the path of movement of the cam roll 6 so that said cam roll will not engage the said lever. This is the position which the lever 2 is caused to assume in starting the machine, and the lever remains in this position throughout the normal rotation of the shaft 1. In order to throw the lever 2 from the position illustrated in full lines to the position indicated in dotted lines in Fig. 3, a lever 14 is mounted upon a stud shaft 15 and is provided with an upwardly extending arm 16 on which is mounted a roll 17. This roll is arranged to engage a cam 18 carried by a block 19 attached to the hub of the lever 2. Said block is also provided with a surface 20 substantially parallel with the plane of movement of the lever 14. When the parts are in stopping positions as illustrated in the drawings and the lever 14 is swung to the 100 left (Fig. 2^a) the roll 17 will engage the cam 18 and move the lever 2 to the position illustrated in dotted lines in Fig. 3. When the lever 14 is moved back to the position indicated in the drawing the lever 2 will be 105 returned to the position shown in full lines in Fig. 3 by a coiled spring 21, mounted in a bore 22 in the shaft 3 and engaging the block 19, the said spring being held in position with relation to said block by means 110 of a shouldered pin 23. As illustrated in Fig. 5 the shaft 3 is cut away at 24 to permit movement of the lever 2 and the block 19 longitudinally of the shaft. 115

The lever 14 is swung to the left (Fig. 130

2^a) to throw the parts of the mechanism for arresting the forward rotation of the shaft out of relative operating positions by means of a rod 25 connected with an arm 26 of 5 said lever and operated by a foot treadle not shown. The rod 25 is provided at its upper end with a slot 27 through which passes a pin 28 secured in the arm 26, thereby providing a lost motion connection between the 10 arm 26 and the treadle rod. When the lever 14 is swung to the left (Fig. 2^a) a sufficient distance to carry the roll 17 on to the surface 20 of the block 19 so that the lever 2 is moved to the position indicated in dotted 15 lines in Fig. 3, the lever 14 is latched in position by a latch 29 pivotally mounted on the extremity of an arm 30 preferably formed integral with the lever 14, said latch being provided with a shoulder 31 which 20 drops behind a catch plate or bar 32. When the treadle is released the treadle rod 25 moves upwardly under the influence of the spring connected with the treadle, and the latch 29 is unlatched from the catch plate 25 32 by a shoulder 25^a on the treadle rod which engages the under side of the latch and lifts the same. The lever 14 is then moved to the right (Fig. 2^a) by a plunger 33 mounted in a bore in the frame and engaged by a coil spring 34.

It is desirable that the devices for arresting the forward rotation of the shaft be arranged to be thrown into relative operating positions always at a predetermined point 35 in the rotary movement of the shaft in order that the stop mechanism may act in a reliable and uniform manner in arresting the forward rotation of the shaft, imparting a return movement thereto and bringing the 40 shaft to rest at a constant position. To insure these results a lever 35 is pivoted upon a stud 36 below the shaft 1 and is provided with a forwardly extending arm upon which is mounted a cam roll 37. This cam roll is 45 held in engagement with the hub of the hand wheel 7 by a coiled spring 39 surrounding the stem of a plunger 40 mounted in a bore in the lever, the head of which engages a lug 41 on the frame, said spring 50 acting against the head of the plunger and the end of the bore in the lever respectively. The hub portion of the hand wheel 7 which is engaged by the roll 37 is cylindrical in 55 form except at one point thereon, at which point is formed a rise 42 constituting a cam which when it is brought into engagement with the roll 37 swings the lever 35 to the right (Figs. 2^a and 2^b). The lever 35 is provided with a rearwardly projecting arm 60 43 constructed to form a catch 44. The lever 14 is provided with an arm 45 preferably constructed integral therewith having a shoulder 46 formed thereon. When the lever 14 is swung to the left (Figs. 2^a and 2^b) to throw the stop mechanism out

of operation, the shoulder 46 on arm 45 is carried above the catch 44 on the lever 35. With the lever 14 in running position, and with the lever 35 in the position illustrated in Figs. 2^a and 2^b, the shoulder 46 being located above the catch 44, movement of the lever 14 to stopping position upon the release of the shoulder 31 on the latch 29 from the catch plate 32 is prevented by the engagement of the shoulder 46 with the catch 44. Upon the engagement, however, of the rise 42 on the hub of the hand wheel 7 with the roll 37 the lever 35 is moved to the right (Figs. 2^a and 2^b), carrying the catch 44 out of engagement with the shoulder 46 on the arm 45, permitting the lever 14 to move to the position shown in Fig. 2^a so that the lever 2 may then move under the action of the spring 21 to stopping position. It will therefore be apparent that the devices for arresting the forward rotation of the shaft will be thrown into relative operating positions always at the same point in the revolution of the main shaft 1 regardless of the time at which the treadle is released.

The roll 6 engages the lever 2 always at the same point in a revolution of the main shaft, and the devices for arresting the forward rotation of the shaft are therefore always brought into action at the same point in a revolution of the shaft.

As above stated, it is desirable after the forward rotation of the shaft has been arrested and a return movement has been imparted thereto to free the thread from the needle to stop the shaft always at a certain and definite point in the rotation thereof. To this end a brake lever 47 is pivotally mounted upon a stud 48 and carries a brake shoe 49 arranged to engage a rise 50 formed on a cylindrical flange constituting a part of the hand wheel 7. The brake shoe 49 is pivotally connected with the lever 47 by the pin 51 arranged so that when the brake shoe is in engagement with the rise 50 the axis of the brake shoe 49 will be slightly in advance of the line connecting the axis of the lever 47 and the axis of the shaft 1. With this construction when the shaft 1 has been reversed and the rise 50 has been brought into engagement with the brake shoe, the brake shoe will be forced tightly into engagement with the surface of the rise by the friction between the rise and the shoe. The rise 50 is located in a definite predetermined position with relation to the main shaft 1 and to the rise 42. The reverse movement of the main shaft 1 is therefore always arrested at a definite predetermined point in a rotation of the shaft 1 and in a cycle of operations of the machine.

The lever 47 is swung to the left (Figs. 2^a and 2^b) to bring the brake shoe 49 into position to engage the rise 50 by a plunger

52 mounted in the same bore in which the plunger 33 is mounted, and also operated by the spring 34. The movement of said lever to the left is limited by a stop 53 which is engaged by an arm 54 on the lever. When the lever 14 is swung to the left (Figs. 2^a and 2^b) from stopping to running position, the lever 47 is swung to the right to carry the brake 49 out of engagement with the surface of the rise 50 by the engagement of the end of the arm 30 with a surface 55 on the lever 47. When the lever 14 is swung from running to stopping position the arm 30 moves to the left, permitting the lever 47 to swing to the left under the action of the spring 34 to bring the brake shoe 49 into position to engage with the rise 50.

In the mechanism described it will be apparent that the movement of the cam roll 6 along the surface 5 of the lever 4, the movement of the lever 2 about the stud 3, and the extent of compression of the air within the cylinder 11 due to the inward movement of the piston connected with said lever, will depend on the speed at which the shaft 1 is rotating at the time that the rebound devices are brought into action. The velocity of the return movement of the shaft 1 which depends upon the compression produced in the cylinder 11 will vary with the velocity of the forward movement of the shaft 1 at the time that the roll 6 engages the lever 2. It will also be apparent that variations in the velocity of the return movement of the shaft will tend to produce variations in the positions at which the reverse movement of the shaft is arrested by the brake mechanism. It is assumed, however, that during the operation of the machine, the shaft will be rotated at or above a predetermined speed necessary for rapid and efficient work in the machine in which the stop mechanism is embodied. In order that the stop mechanism may operate in a uniform and reliable manner to arrest the forward rotation of the shaft, impart a return movement thereto, and stop the shaft always at a predetermined constant position, in the present invention a brake device is provided to slow the shaft down to a predetermined speed before the rebound mechanism is brought into action. In the structure illustrated, the said device comprises a pair of centrifugal clutch members 57 and 58 pivotally mounted on studs 59 and 60 carried by the hand wheel 7 and provided with weighted extremities 61 and 62 respectively. Clutch shoes 63 and 64 are mounted on the members 57 and 58 respectively and when the said members are thrown outwardly by centrifugal action the clutch shoes engage an inner clutch surface 65 upon a brake wheel 66 mounted loosely on the shaft 1. The clutch members 57 and 58 are connected

by a link 67 so that they move outwardly and inwardly into and out of engagement with the clutch surface 65 in unison. A coiled spring 68 is connected at one end with the weighted extremity of the member 58 and at the other end with a relatively fixed point on the hand wheel, the tension of which spring is just sufficient to maintain the clutch shoes 63 and 64 withdrawn from engagement with the clutch surface 65 when the speed of rotation of the shaft 1 equals or is less than a certain predetermined speed, but to permit the members 57 and 58 to be thrown outwardly to bring the clutch shoes into engagement with said brake surface 65 and cause the brake wheel 66 to rotate with the shaft when the speed of rotation of said shaft exceeds the predetermined speed.

In order that the tension of the spring 68 may be varied as desired, said spring is adjustably connected with the hand wheel by any convenient form of adjustable connection. Upon the outside of the brake wheel 66 is formed a brake surface 69 about which passes a brake band 70 having one extremity thereof fixed at 71 to the frame of the machine. A block 72 is secured to the other extremity of the brake band, and a rod 73 is threaded into said block and passes through perforated lugs 74 and 75 projecting from the frame. A coiled spring 76 surrounds the rod 73 below the lug 74 and engages said lug and an adjustable collar 77 mounted upon the rod 73, thereby tending to move the rod 73 in a direction to tighten the brake band 70. The collar 77 is held from longitudinal movement on the rod 73 by a pin 78 which may be placed in any one of a series of holes in the rod. The rod 73 is held from turning movement in the lugs 74 and 75 by a pin 79 which operates in a slot in the lug 75.

When the parts of the stop mechanism are in running position the brake band is maintained in a loose condition about the brake wheel 66 by an arm 80 secured to the lever 14 so as to move therewith about the stud 15. Upon movement of the lever 14 to the left (Figs. 2^a and 2^b) to throw the parts of the stop mechanism out of operating positions, the extremity of the arm 80 engages a collar 81 fixed to the rod 73 and moves the rod 73 upwardly through the lugs 74 and 75, and thereby loosens the brake band. When the lever 14 is in its extreme left-hand position the shoulder 46 is somewhat above the catch 44 so that upon the release of the treadle a slight movement of the lever 14 to the right is permitted before the shoulder 46 engages the catch 44. This movement of the lever 14 is sufficient to carry the extremity of the arm 80 out of engagement with the collar 81, and the brake band is then immediately tightened about the

brake wheel by the action of the spring 76. Therefore the brake mechanism is applied to the shaft immediately upon the release of the treadle. The relation of the rise 42 to the cam roll 6 is such that the shaft 1 must make at least substantially half a revolution after the lever 2 is thrown into operative position before the roll 6 engages the cam surface of the said lever. The shaft 1 therefore makes at least half a revolution after the release of the treadle and the application of the brake before the mechanism for arresting the forward rotation of the shaft is brought into action, thus securing a material braking interval. Assuming that the shaft is rotating at a speed greater than that which is necessary to throw the clutch shoes 63 and 64 into engagement with the clutch surface 65 when the treadle is released, the said clutch shoes will be maintained in engagement with the said clutch surface and will tend to rotate the brake wheel 66 against the braking action of the brake band 70 until the shaft is rotating at the predetermined speed, when the clutch shoes will be withdrawn from engagement with the clutch surface of the brake wheel, thereby releasing the shaft from the brake and permitting it to continue to rotate at the predetermined speed by reason of the inertia of the machine. In case it is desired to increase the minimum braking interval secured, the relative positions of the roll 6 and the rise 42 may be changed so that the shaft will make at least nearly a complete revolution after the treadle is released and the brake applied before the roll 6 engages the surface 5 of said lever.

It is desirable on certain occasions to turn the main shaft of the machine by hand to operate the parts of the machine, or to place the parts thereof in any desired position.

When the parts of the stop mechanism are in stopping positions it is impossible to impart more than a partial rotation in either direction to the main shaft of the machine. In order to throw the parts of the stop mechanism into starting position without depressing the treadle and thereby throwing the machine into driving connection with the driving shaft, a lever 82 is pivotally mounted on the stud 48 and is provided with an upwardly extending arm 83 on which is mounted a roll 84 arranged to engage the under surface 85 of the arm 45 of the lever 14. The lever 82 is also provided with a forwardly extending operating arm 86. When the said lever is swung to the left (Figs. 2^a and 2^b) the lever 14 is swung to the left to throw the parts of the stop mechanism into starting position by the engagement of the roll 84 with the under surface 85 of the arm 45, the slot 27 in the upper end of the treadle rod permitting

the treadle to be maintained in released position. When the lever 14 is moved to its extreme left-hand position the roll 84 enters a recess 87 behind the surface 85 and locks the lever 14 and the parts connected therewith in inoperative position.

During the sewing operation, the machine is driven by means of a belt 88 passing about the hand wheel 7, and about a pulley 89 mounted in the base of the machine. The pulley 89 is connected through beveled gears 90 with a sleeve 91 mounted on the driving shaft 92, and carrying one member 93 of the main driving clutch. The driving shaft 92 carries the other member 94 of the clutch, and also carries the driving pulley 95, through which motion is imparted to the driving shaft. The engagement of the members of the driving clutch is controlled from a treadle 96 connected by a link 97 with a clutch operating wedge 98. When the treadle is released, the clutch members are disengaged, thus disconnecting the main shaft of the machine from the driving shaft 92. Connecting mechanism is provided between the treadle 96 and the rod 25, so that when the treadle is depressed the parts of the stop mechanism will be thrown into running positions, and that when the treadle is released the stop mechanism will be thrown into operation. In the construction illustrated, the lower end of the rod 25 is secured within a collar or sleeve 99 which is pivoted to the end of an arm 100 fast upon a rock shaft 101 mounted in bearings 102 and 103 on the frame of the machine. A second arm 104 is fast to the forward end of the rock shaft 101, and is connected by a rod 105 to the forward end of the treadle 96. With this construction the rod 105 will be drawn downwardly upon the depression of the treadle to engage the main driving clutch in the base of the machine, and when the treadle is released and rises under the influence of its actuating spring, the rod 25 will be lifted.

Briefly described, the operation of the driving and stopping mechanism in the illustrated embodiment of the invention is as follows: Starting with the parts in stopping positions as they are shown in the drawings, as the operator depresses the treadle to start the machine, the lever 14, through its connection with the treadle, is swung to the left about the shaft upon which it is pivoted, thereby throwing the lever 2 longitudinally of the shaft 3 out of the path of the cam roll 6, and disengaging the brake shoe 49 from the rise 50. As the lever 14 swings to running position, the end of the arm 80 acts to lift the collar 81 and thereby loosen the brake bands 70 about the brake wheel 66. While the machine is running, the brake shoes 63 and 64 are engaged with the brake wheel 66, and the brake

6 wheel is thereby rotated at the same speed as that of the main shaft of the machine. The lever 14 is held in running position by the engagement of the shoulder 31 behind 5 the catch plate 32, and the slot 27 permits the pressure upon the treadle to be varied to change the speed of the machine without affecting the lever 14. Upon the release of the treadle by the operator at the completion 10 of the sewing operation, it rises under the influence of its actuating spring until the shoulder 25^a on the treadle rod engages beneath the end of the latch 29, thereby lifting the latch and disengaging the shoulder 31 from behind the catch plate 32. The 15 lever 14 is thereby released, and is swung to the right by the action of the spring 34 until its movement is arrested by the engagement of the shoulder 46 with the catch 20 44 carried by the lever 35, which is then in the position shown in Figs. 2^a and 2^b. The movement of the lever 14 from the position in which it is held by the latch 31 to the 25 position in which it is stopped by the catch 44 is not sufficient to permit the cam lever 2 to be moved into the path of the cam roll 6, but is sufficient to release the end of the arm 80 from the collar 81 and allow the 30 brake band 70 to be tightened upon the brake wheel 66 by the action of the spring 76. The braking devices which act to reduce the speed of the shaft to a predetermined speed before the rebound devices are thrown into operation therefore become active 35 almost immediately upon the release of the treadle. As the main shaft of the machine continues to rotate, the rise 42 is engaged by the roll 37, thereby swinging the lever 35 in a direction to disengage the catch 44 from beneath the shoulder 46. The 40 lever 14 is then swung farther to the right, until it reaches the position shown in Figs. 2^a and 2^b, allowing the cam lever 2 to be moved longitudinally of the shaft 3 into the 45 path of the cam roll 6, and releasing the lever 47, which is swung on its pivot by the action of the spring 34 to bring the brake shoe 49 into position to engage the rise 50. Before the cam roll 6, however, engages the 50 cam lever 2, the speed of the main shaft of the machine will have been reduced to a predetermined speed by the coöperative action of the brake shoes 64, the brake wheel 66, and the brake band 70. Upon the engagement 55 of the cam roll 6 with the cam lever 2, the cam roll is swung about the shaft 3 in a direction to cause the piston 10 to compress the air within the cylinder 11. When the resistance of the air within the 60 cylinder is sufficient to overcome the momentum of the machine, the forward rotation of the main shaft of the machine is arrested. The reaction of the compressed air within the cylinder then forces the piston 65 upwardly in the cylinder, and the lever 2

is thereby swung in the reverse direction. During this movement of the lever through the coöperative action of the cam surface 5 of the lever and the cam roll 6, a reverse rotation is imparted to the shaft. Reverse 70 rotation of the shaft is arrested at a predetermined point by the engagement of the brake shoe 49 with the rise 50.

Having explained the nature and object of the invention, and specifically described 75 one form of mechanism in which it may be embodied, what I claim is:—

1. A stop mechanism, having, in combination, a shaft, a rebound mechanism for arresting the forward rotation of the shaft 80 and for imparting thereafter a return movement to the shaft, and a brake device acting in timed relation to the rebound mechanism to slow the shaft down to a predetermined speed before the rebound mechanism is 85 brought into action, substantially as described.

2. A stop mechanism, having, in combination, a shaft, devices for arresting the forward rotation of the shaft, a brake device 90 acting to slow the shaft down to a predetermined speed and then to release the shaft, and means to apply the brake before the arresting devices are brought into action, substantially as described.

3. A stop mechanism, having, in combination, a shaft, rebound devices for arresting the forward rotation of the shaft and for imparting thereafter a return movement to the shaft, a brake device for the shaft, 100 means to apply the brake, and mechanism acting automatically to bring the rebound devices into action at least a predetermined interval after the brake is applied, substantially as described.

4. A stop mechanism, having, in combination, a shaft, mechanism for arresting the forward rotation of the shaft, a brake device acting to slow the shaft down to a predetermined speed and then to release the shaft, means to apply the brake, and mechanism acting automatically to bring the arresting mechanism into action at least a predetermined interval after the brake is applied, substantially as described.

5. A stop mechanism, having, in combination, a shaft, devices for arresting the forward rotation of the shaft, a brake device acting to slow the shaft down to a predetermined speed and then to release the 123 shaft, mechanism for applying the brake, and means to bring the arresting devices into action at a definite point in the rotation of the shaft after the brake is applied, said devices and means being constructed 125 and arranged to maintain said devices out of action at least a predetermined interval after the brake is applied, substantially as described.

6. A stop mechanism, having, in com- 130

bination, a shaft, rebound devices for arresting the forward rotation of the shaft and for imparting thereafter a return movement to the shaft, a brake device acting to slow the shaft down to a predetermined speed and then to release the shaft, mechanism for bringing the rebound devices into action at least a predetermined interval after the brake is applied, and means to arrest the return movement of the shaft at a predetermined constant position substantially as described.

7. A stop mechanism, having, in combination, a shaft, mechanism for arresting the forward rotation of the shaft comprising a movable member having a curved cam surface formed thereon, extending about the axis of rotation of the shaft in a direction substantially parallel with the plane of rotation of the shaft, a second member mounted to rotate with the shaft and arranged to engage the cam surface of the first member and move said member, and means to yieldingly resist the movement of the first member, substantially as described.

8. A stop mechanism, having, in combination, a shaft, a rebound mechanism for arresting the forward rotation of the shaft and for imparting thereafter a return movement thereto comprising a movable member having a curved cam surface formed thereon, extending about the axis of rotation of the shaft in a direction substantially parallel with the plane of rotation of the shaft, a second member mounted to rotate with the shaft and arranged to engage the cam surface on the first member and move said member in one direction, and mechanism acting to yieldingly arrest the said movement of the first member and to thereafter move said member in the opposite direction to impart a return movement to the shaft, substantially as described.

9. A stop mechanism, having, in combination, a shaft, mechanism for arresting the forward rotation of the shaft and for imparting thereafter a return movement thereto comprising an oscillatory lever pivoted on an axis substantially parallel with the axis of rotation of the shaft and having a cam surface formed thereon; a roll mounted to rotate with the shaft and arranged to engage the cam surface of the lever to move the lever about its axis in one direction, a pneumatic device acting to yieldingly arrest the said movement of the lever and to impart thereafter a movement of the lever in the opposite direction to impart a reverse movement to the shaft, substantially as described.

10. A stop mechanism, having, in combination, a shaft, mechanism for arresting the forward rotation of the shaft, a brake device to slow the shaft down to a predetermined speed before the arresting mecha-

nism is brought into action comprising a member mounted to rotate with the shaft and arranged to be thrown outwardly when the shaft is rotating above the predetermined speed, a second member arranged to be engaged by said first member upon outward movement thereof, and means to withdraw said first member from engagement with the second member when the shaft is rotating at or below the predetermined speed, substantially as described.

11. A stop mechanism, having, in combination, a shaft, mechanism for arresting the forward rotation of the shaft, means to slow the shaft down to a predetermined speed before the arresting mechanism is brought into action, comprising a member mounted to rotate with the shaft and arranged to be thrown outwardly when the shaft is rotating above a predetermined speed, a brake wheel mounted to rotate freely during the normal rotation of the shaft and arranged to be engaged by said member upon outward movement thereof to cause the brake wheel to rotate with said member, means to withdraw said member from engagement with the brake wheel when the shaft is rotating at or below the predetermined speed, a brake for retarding the rotation of the brake wheel, and means to apply the brake to the brake wheel before the arresting mechanism is brought into action, substantially as described.

12. A stop mechanism, having, in combination, a shaft, mechanism for arresting the forward rotation of the shaft, and a centrifugal brake device acting to slow down the shaft to a predetermined speed and then to release the shaft before the arresting mechanism is brought into operation, substantially as described.

13. A stop mechanism, having, in combination, a shaft, mechanism for arresting the forward rotation of the shaft, means to throw the said mechanism into and out of operating position comprising a pivoted lever arranged when in one position to maintain said arresting mechanism out of operating position and when in another position to permit the arresting mechanism to be thrown into operating position, an arm on said lever, a reciprocatory catch member arranged to engage said arm to prevent movement of said lever in a direction to permit the arresting mechanism to be thrown into operation, and means to move said reciprocatory member out of engagement with said arm at a definite point in each rotation of the shaft, substantially as described.

14. A stop mechanism, having, in combination, a shaft, mechanism for arresting the forward rotation of the shaft and for imparting thereafter a return movement thereto comprising an oscillatory lever having a cam surface formed thereon and arranged to

move longitudinally of its axis, a member mounted to rotate with the shaft and arranged to engage the lever and move said lever about its axis in one direction, a rebound device acting to yieldingly arrest the said movement of the lever and then to move said lever in the opposite direction to impart a return movement to the shaft comprising a cylinder, a piston operating in the cylinder and connected with the lever, means to move said lever longitudinally of its axis into and out of the path of said member comprising a cam carried by said lever, a second lever, a member carried thereby for engagement with the said cam, means to move the second lever about its axis in one direction to engage the second member with said cam and to move the first lever out of the path of the first member, 20 and a spring for moving the first lever into the path of the first member upon movement of the second lever in the opposite direction, substantially as described.

15. A stop mechanism, having, in combination, a rebound mechanism for arresting the forward rotation of the shaft and for imparting thereafter a return movement thereto, a brake device arranged to slow the shaft down to the predetermined speed 25 and then to release the shaft, means under control of the operator to apply the brake, and mechanism tripped by the action of said means in applying the brake and acting to bring the arresting mechanism into 30 action at a definite point in a rotation of the shaft and at least a predetermined interval after the brake is applied, and means to arrest the return movement of the shaft at a definite position, substantially as described.

16. A stop mechanism, having, in combination, a shaft, an oscillatory lever having a cam surface formed thereon and arranged to move longitudinally of its axis, a roll arranged to rotate with the shaft for engagement with the cam surface of said lever, a spring for moving said lever into the path of said roll, a cam carried by the first lever, a second lever, a member carried by the second lever and arranged to engage said cam and move the first lever longitudinally of its axis out of the path of said roll, an arm on the second lever, a catch member for engagement with said arm to prevent movement of the second lever in a direction to permit the first lever to be moved into the path of said roll, means to move said catch member out of the path of said arm at a definite point in a revolution of the shaft, a brake for arresting the return movement of the shaft at a definite constant position, an arm carried by the second lever for moving the brake out of operative position upon movement of the second lever in a direction to throw the first lever out of the

path of the roll, and means to throw the brake into operative position when the first lever is moved into the path of said roll, substantially as described.

17. A stop mechanism, having, in combination, a shaft, a rebound device for yieldingly arresting the forward rotation of the shaft and for thereafter imparting a return movement thereto, a brake for arresting the return movement of the shaft at a definite constant position, a lever arranged when in one position to maintain said device and said brake out of operative position and when in another position to permit said device and said brake to be thrown 75 into operative position, a treadle and connections therefrom for moving said lever from the second to the first position, a spring for moving said lever from the first to the second position, a latch for maintaining the 80 lever in the first position until the treadle is completely released, and means to disengage said latch upon the complete release of the treadle, substantially as described.

18. A stop mechanism, having, in combination, a shaft, rebound devices for arresting the forward rotation of the shaft and for imparting thereafter a return movement to the shaft, a brake device to slow the shaft down to a predetermined speed 90 and then to release the shaft, means to apply the brake upon the release of the treadle, and mechanism tripped by the release of the treadle and acting automatically to bring the rebound devices into action at 95 100 a predetermined point in the rotation of the shaft and at least a predetermined interval after the brake is applied, substantially as described.

19. A stop mechanism, having, in combination, a shaft, rebound devices for arresting the forward rotation of the shaft and for imparting thereafter a return movement to the shaft, a brake device to slow the shaft down to a predetermined speed 105 and then to release the shaft, means to apply the brake upon the release of the treadle, mechanism tripped by the release of the treadle and acting automatically to bring the rebound devices into action at a predetermined point in the rotation of the shaft and at least a predetermined interval after the brake is applied, and means to throw the rebound devices out of relative operating 110 115 positions and simultaneously to release the brake upon the depression of the treadle, substantially as described.

20. A stop mechanism having in combination, a shaft, a main driving mechanism therefor, speed reducing mechanism rendered active when the main driving mechanism is thrown out, means for rendering the speed reducing mechanism inactive allowing the shaft to continue its rotation under its momentum, and mechanism for stopping 125 130

the shaft after the speed reducing mechanism becomes inactive.

21. A stop mechanism having in combination a shaft, a main driving mechanism therefor, speed reducing mechanism rendered active when the main driving mechanism is thrown out, means for rendering the speed reducing mechanism inactive, and rebound mechanism acting after the speed reducing mechanism becomes inactive to arrest the forward rotation of the shaft and turn the shaft back to stopping position.

22. A stop mechanism, having in combination, a shaft, a main driving mechanism therefor, a friction brake rendered active when the main driving mechanism is thrown out, means for rendering the brake inactive when the speed of the shaft has been reduced to a certain point and rebound mechanism acting to arrest the forward rotation of the shaft and turn the shaft back to stopping position.

23. A stop mechanism having in combination, a shaft, a main driving mechanism therefor, a friction brake rendered active when the main driving mechanism is thrown out, means for rendering the brake inactive when the speed of the shaft has been reduced to a certain point, rebound mechanism acting after the brake is inactive to arrest the forward rotation of the shaft and turn the shaft back to stopping position after it is freed from the brake, and means for insuring at least a predetermined interval between the application of the brake and the action of the rebound mechanism.

24. A stop mechanism having in combination a shaft, a main driving mechanism therefor under control of the operator, mechanism rendered active when the main driving mechanism is thrown out by the operator for slowing down the shaft to a predetermined speed and mechanism acting initially while the shaft is rotating at the reduced speed to arrest the forward rotation of the shaft and turn it back to stopping position.

25. A stop mechanism having in combination, a shaft, a main driving mechanism therefor under control of the operator, mechanism rendered active when the main driving mechanism is thrown out by the operator for slowing down the shaft to a predetermined speed and rebound mechanism acting initially while the shaft is rotating at the reduced speed to arrest the forward rotation of the shaft and turn it back to stopping position.

26. A stop mechanism having in combination a shaft, driving mechanism for the shaft, speed controlled speed reducing mechanism rendered active when the driving mechanism is thrown out, and mechanism for throwing out the speed reducing mechanism when the speed is reduced to a predetermined point.

27. A stop mechanism having in combination a shaft, driving mechanism for the shaft, speed reducing mechanism rendered active when the driving mechanism is thrown out, mechanism for throwing out the speed reducing mechanism when the speed is reduced to a predetermined point, and means for stopping the shaft while it is rotating under its momentum.

28. A stop mechanism having in combination a shaft, driving mechanism for the shaft, a centrifugal brake rendered active when the driving mechanism is thrown out, and inactive when the speed of the shaft has been reduced to a predetermined point, and means for stopping the shaft after the brake is inactive.

29. A stop mechanism having in combination a shaft, driving mechanism for the shaft, a centrifugal brake device arranged to slow the shaft down to a predetermined speed, and then to release the shaft, and means acting to apply the brake when the driving mechanism is thrown out.
